Myers & Webster.

UNITED STATES PATENT OFFICE.

BERNARD P. WAGNER, OF SIDNEY, OHIO, ASSIGNOR OF TWO-THIRDS TO
WILLIAM H. WAGNER AND MILTON M. WAGNER, BOTH OF SAME PLACE.

CASH-RECODER.

SPECIFICATION forming part of Letters Patent No. 434,217, dated August 12, 1890.

Application filed March 27, 1890. Serial No. 345,576. (No model.)

To all whom it may concern:

Be it known that I, BERNARD P. WAGNER, a citizen of the United States of America, residing at Sidney, in the county of Shelby and 5 State of Ohio, have invented certain new and useful Improvements in Cash-Recorders, of which the following is a specification, reference being had therein to the accompanying drawings.

10 My invention relates to certain improvements in cash- recorders; and it consists in certain details of construction and combination of parts, which will first be described in connection with the accompanying drawings, 15 and then pointed out in the claims.

Figure 1 of the drawings is a perspective view of the apparatus, one side and other portions of the casing being broken out to disclose the construction and arrangement of the 20 operative mechanism. Fig. 2 is an elevation of the left-hand side of the apparatus, partly in section.

Referring to the drawings, 1, 2, 3, 4, 5, 6, 7, 25 and 8 represent the fixed portions of the casing constructed in the form illustrated.

A represents what is termed the "cylinder," it being a segmental cover for the till C. It is rocked backward and forward on two arms B, secured to its ends and pivoted to the sides 30 1 of the casing on the inner side.

D are two brackets, secured in a horizontal position to the back wall 3, and also to the middle face-plate 7 of the casing, they being provided with down-hanging lugs e, in 35 which is journaled the paper-roll E, on which is to be wound a strip of blank paper F of any desired length.

In the rear ends of two arms G, pivoted at their forward ends to the brackets D, is secured what I term a "tension-bar" H, made, 40 preferably, of a rectangular strip of wood. This bar is designed to rest upon the roll of paper F, thus serving to keep the paper smooth and even, and also to give tension to the strip of paper while the latter is being transferred to the winding-drum.

I is the winding-drum, which is journaled in the brackets D a short distance forward of the paper-roll, the drum being provided on 45 one end with a ratchet-wheel J, as seen in Fig. 1, with which engages a dog j, pivoted

on one of the brackets D to prevent retrograde movement of the drum.

K is a horizontal lever, pivoted at one end to a bracket k, secured to the inner side of the middle face-plate 7 of the casing. This lever carries at its free end a pivoted link K', which is in engagement with a pin l on the lower end of a bent arm L, pivoted centrally to the ratchet-wheel, and carrying at its upper end 60 a pivoted pawl L' in engagement with the ratchet-wheel for turning the winding-drum forward.

M is a locking-bolt provided with a laterally-projecting pin m. This bolt, which locks 65 the cylinder, is vertically movable in keepers N, (seen in dotted lines in Fig. 1 and in full lines in Fig. 2,) secured to the inner side of the middle face-plate 7 of the casing, the lower end of the bolt taking into a recess a (seen 70 dotted) in the cylinder.

O is the lever-operating rod or push-rod, which is a short rod of metal, having its inner end turned upward at a right angle, as at o, and passed through a perforation in lever 75 K, its outer end, which extends outside of the casing through a hole in the face-plate 7, being provided with a push-button o'. This push-rod is provided upon its under side with what I term a "key," consisting of a downwardly and rearwardly inclined projecting piece o², which is preferably formed integral 80 with the rod, and which is in engagement with the pin m on bolt M, as clearly shown in Fig. 1.

P is a bell-crank, pivoted at p to one of the brackets D in such position that its vertical arm will rest against the rear side of the horizontal lever K, the horizontal arm of the bell-crank being provided with a weight w, for a 90 purpose which will be presently stated.

Q is a lid, hinged at q to the part 6 of the casing and covering the paper-roll and winding-drum. In the central portion of this lid, in the upper side, there is formed a rectangular recess R, having a depth of about half the thickness of the lid, and at the upper and lower edges of this recess the lid is slotted transversely, as at r and r'. A glass plate S, of about two-thirds the width of this recess, 95 is inserted therein in such a manner as to permit the paper, while being transferred 100

from the paper-roll to the winding-drum, to pass freely under it, as shown, there being an opening left at r^2 , where the paper is exposed for the purpose of receiving the record to be made by the salesman.

T is an arm on the cylinder A, for the purpose of causing an alarm to be sounded on a gong-bell U when the cylinder is thrown back, the operation of sounding this alarm being manifest without description. The cylinder, when unlocked, is thrown back by means of a leaf-spring V, secured at one end to the inner side of the face-plate 7, its free end being in engagement with the front side of a right-angular lip a' , secured to the cylinder, as seen in dotted lines in Fig. 1. The money box or till C is placed in the bottom portion of the casing and against the lower face-plate 8, the cylinder, when down, resting upon this face-plate. The upper face-plate 5 may, if desired, be provided with a plate of glass, on which to place any suitable inscription—as, for instance, "Your purchase is recorded here."

The operation of my cash-recorder, which is very simple, is as follows: The salesman first makes his entry upon the paper through the opening r^2 in the recess R in the lid. He then pushes on the lever-operating rod O, which swings lever K backward, and thus, through the medium of the pawl and ratchet-wheel, turns the winding-drum, drawing that portion of the paper containing the entry forward under the glass plate, where the entry is left for inspection until the recorder is again operated. In this inward movement of the rod O its key o^2 , by reason of its inclination from a plane parallel with that of the rod O itself, raises the locking-bolt M free of the cylinder, permitting the latter, impelled by the spring V, to rock backward, and thus uncover the till and at the same time sound an alarm. When the salesman ceases to press upon the rod, the weight w will cause the bell-crank to swing upon its pivot and press the lever K and rod O back to their normal positions, when the locking-bolt will drop by

gravity. The salesman draws the cylinder back to its normal position by taking hold of the knob a^2 .

Having thus described my invention, what I claim as new, and desire to secure by Letters Patent, is—

1. In a cash-recorder, the combination, with the winding-drum carrying a ratchet-wheel and a pawl-carrying arm pivoted on said wheel, of a pivoted lever carrying a link which is in engagement with said arm, a till-cover, a bolt for locking said cover, and a push-rod connected to said lever and provided with a key in engagement with the bolt, whereby as the winding-drum is turned the cover is simultaneously unlocked.

2. In a cash-recorder, the combination, with the winding-drum carrying a ratchet-wheel and a pawl-carrying arm pivoted on said wheel, a pivoted lever carrying a link which is in engagement with said arm, and a till-cover, of a bolt for locking said cover, provided with a laterally-projecting pin, and a push-rod connected with the lever and provided with a downwardly and rearwardly inclined key in engagement with the pin on the locking-bolt, for the purposes set forth.

3. In a cash-recorder, the combination, with the winding-drum provided with a ratchet-wheel, the pawl-carrying arm pivoted on said wheel, the pivoted lever carrying a link in engagement with said arm, the locking-bolt, and the combined push-rod and key, all constructed and arranged substantially as described, of the pivoted bell-crank, one of its arms being provided with a weight and its other arm resting against the rear side of the lever, whereby the said lever and combined push-rod and key are automatically returned to their normal positions and the locking-bolt is permitted to drop.

In testimony whereof I affix my signature in presence of two witnesses.

BERNARD P. WAGNER.
